UNITED STATES PATENT OFFICE.

PAUL M. RAINY, OF GLEN RIDGE, NEW JERSEY, ASSIGNOR TO WESTERN ELECTRIC COMPANY, INCORPORATED, OF NEW YORK, N. Y., A CORPORATION OF NEW YORK.

DISTRIBUTING APPARATUS.

1,375,728.

Specification of Letters Patent. Patented Apr. 26, 1921.

Application filed August 28, 1917. Serial No. 188,587.

To all whom it may concern:

Be it known that I, PAUL M. RAINY, a citizen of the United States, residing at Glen Ridge, in the county of Essex and 5 State of New Jersey, have invented certain new and useful Improvements in Distributing Apparatus, of which the following is a full, clear, concise, and exact description.

This invention relates to an improved 10 type of current impulse distributing apparatus, particularly adapted for use in multiplex printing telegraph systems, although obviously not limited to such use.

The principal objects of this invention 15 are to provide distributing apparatus of the above type which is flexible, easy to construct, and efficient in operation.

For the accomplishment of the above objects the invention contemplates the provision 20 of a plurality of segmented distributor faces preferably arranged in separate parallel planes. The segments are segregated so that the receiving and receiving local segments are carried on one distributor face, 25 the sending and sending local segments on another distributor face, and the correcting segments on still another distributor face. The distributor faces are mounted parallel to one another and are normally stationary, 30 but are adapted to be orientated or turned through a complete revolution, when necessary, as for example, when it is desired to regain synchronism once it is lost. Suitable collector brushes or trailers are carried by 35 distributor arms, mounted on a rotatable shaft, and are adapted to engage and interconnect the segmented distributor rings with the common or continuous rings, there being one pair of brushes for each pair of distributor rings.

While the preferred embodiment of this invention is illustrated in connection with a multiplex telegraph system, it is to be understood that it is equally suitable for 45 other signaling systems wherein it is desirable to distribute current impulses in a predetermined or sequential order.

The above and other features of this invention will be fully set forth in the following description and claims and will be more 50 readily understood by reference to the accompanying drawings, wherein Figure 1 is a side elevation of a plurality of current distributors with one of such distributors shown 55 in cross-section; Fig. 2 is a front view on

line 2, 2 (Fig. 1) of the correcting distributor face; Fig. 2 is a front view on line 3, 3 (Fig. 1) of the sending distributor face; and Fig. 4 is a front view on line 4, 4 (Fig. 1) of the receiving distributor face.

60

Referring first to Fig. 4, the receiving distributor face "R" comprises a plurality of rings which are adapted to be connected in pairs by suitable brushes, one ring of each pair being segmented and one ring of each 65 pair being continuous. Rings 10 and 11 form one pair, of which ring 10 is segmented, these rings being connected by brushes 20 and 21 carried by a distributor arm 25. Rings 12 and 13 form another pair, of 70 which ring 12 is segmented, these two rings being employed for controlling local apparatus when interconnected by brushes 22 and 23. These latter rings are generally employed for the purpose of distributing local 75 impulses to the receiving mechanism, such for example as the local impulses for controlling the printing operation of a telegraph receiving printer.

The sending distributor face "S," like distributor face "R," is likewise composed of a plurality of rings some of which are segmented and others of which are continuous. Segmented ring 30 and continuous ring 31 form one pair of sending rings and are 80 adapted to be connected by brushes similar to those carried by the distributor arm 25. Segmented ring 32 and continuous ring 33 form another pair likewise adapted to be interconnected by suitable trailer brushes 85 carried by a rotatable distributor arm. The former pair of the above-mentioned rings are generally employed for impressing upon a transmission line current impulses in sequential or predetermined order. The latter 90 pair of rings are for the purpose of providing local impulses which may be utilized at the sending station for operating local apparatus, such, for example, as stepping ahead 95 the tape of an automatic transmitter.

100

The correcting distributor face "C" may be used for the purpose of automatically maintaining synchronism, as disclosed in my copending application Serial No. 22,303 filed April 19, 1915. The distributor face 105 C is composed of two rings, one of which is segmented and the other of which is continuous. The segmented ring 40 and the continuous ring 41 are adapted to be interconnected by suitable trailer brushes similar 110

to those illustrated in Fig. 1 in connection with the receiving distributor.

In Fig. 1 the correcting, sending and receiving distributor heads are shown arranged in three parallel planes, suitably mounted on frame supports 26, 27 and 28 respectively. Extending through the center of each of the distributor heads is a rotatable shaft 29. In front of each distributor face and rigidly connected to the rotatable shaft 29 is a distributor arm 25 (only one of which is shown) carrying trailer brushes arranged to sweep over and interconnect the rings of the distributor faces. It is, of course, understood that the two trailer brushes of each pair are electrically connected together.

The trailer arms 25 and shaft 29 may be rotated by means of a motor 15 or any suitable driving mechanism of uniform speed. A fly-wheel 16 is shown connected to the motor shaft for damping fluctuations in the speed of the motor. The fly-wheel may consist of a chamber 16 filled with mercury, or it may be of any other suitable construction.

The distributor heads are mounted stationary on the supports 26, 27 and 28 but are arranged so that they may be orientated or turned through a complete revolution of 360° if desired. For this purpose a handle 17 is provided and connected to each of the distributor heads. In order that the distributor heads may be orientated without disturbing or affecting the circuit connections to the segments of the distributor faces a flexible cable 35 is provided for each distributor containing a plurality of conductors 38 connected to the distributor segments as shown in Fig. 1. The cables 35 are so arranged that when any one of the distributor heads is orientated the slack in the cable will be wound upon the drum portion 36 without rupturing or injuring the circuit connections to any of the distributor segments.

This type of distributor is well suited for various kinds of service where it is necessary that the receiving and sending instruments be kept in synchronism, and is particularly well suited for service on lines where there are a number of receiving stations receiving from a lesser number of sending stations. If for some reason any one of the receiving stations should get out of synchronism with the sending station, the receiving operator at that station may regain synchronism quickly by simply turning the receiving distributor until the signals are received in their proper phase.

In case it is desired to work from different stations two or more channels through one repeating station, it may be necessary to ad-

just the sending distributor in such a way that the impulses from the different stations, will be received at the repeating station in their proper phase. In that event one or more of the sending distributor faces may be orientated until the signals pass at the repeating station in the desired order.

Rigidly supported on the frame of the machine and back of each of the distributor heads is an indicating scale 37 with divisions cut therein to indicate the number of degrees or divisions the distributor faces have been turned. This, however, forms no part of the present invention.

Since the local impulses, which are utilized at the sending station to perform such functions as stepping ahead the tape of an automatic transmitter, etc., must bear a definite phase relation to the signaling impulses, it is essential that the sending and sending local segments of the sending distributor, always bear a fixed relation to one another, and it is not necessary that they be made relatively adjustable. The same is true with respect to the receiving distributor. That is, the receiving and receiving local segments must have a fixed relation with respect to one another so that the local impulses which are utilized at the receiving station to perform such functions as operating the printing magnet, etc., will bear a definite phase relation to the signaling impulses. On the other hand, it is highly desirable for synchronizing purposes that the sending, receiving and correcting segments be made adjustable with respect to one another. By means of applicant's invention the correcting, receiving or sending distributor may be orientated independently of the others, thereby providing a system of great flexibility and one wherein synchronism may be readily established.

What is claimed is:

1. A distributing apparatus comprising a rotatable head, a distributor face carried by said head, segments on said face, a cable containing a plurality of flexible conductors, the conductors of said cable being connected directly to said segments, and means whereby said head may be rotated without altering the connections to said segments.

2. A distributing apparatus comprising a rotatable head, means for rotating said head, a cable wound upon said head and rotatable therewith, a plurality of segments carried by said rotatable head, and circuit connections extending from said cable to said segments.

In witness whereof, I hereunto subscribe my name this 24th day of August A. D. 1917.

PAUL M. RAINES.
